CLAIM

We claim the ornamental design for an exercise device, as shown and described.

DESCRIPTION

FIG. 1 is a perspective view of an exercise device, showing our new design;

FIG. 2 is a front elevational view thereof;

FIG. 3 is a rear elevational view thereof;

FIG. 4 is a top plan view thereof;

FIG. 5 is a right-side elevational view thereof;

FIG. 6 is a bottom plan view thereof; and,

FIG. 7 is a left-side elevational view thereof.

1 Claim, 3 Drawing Sheets

FIG. 6

FIG. 7
